UNITED STATES PATENT OFFICE

134,962

DESIGN FOR A GLASS PLATE OR THE LIKE

Carl T. Sloan, Jeannette, Pa., assignor to The Jeannette Glass Company, Jeannette, Pa., a corporation of Pennsylvania

Application August 27, 1941, Serial No. 163,953

Term of patent 14 years

To all whom it may concern:

Be it known that I, Carl T. Sloan, a citizen of the United States, residing in Jeannette, in the county of Westmoreland and State of Pennsylvania, have invented a new, original, and ornamental Design for a Glass Plate or the like, of which the following is a specification, reference being had to the accompanying drawings forming part thereof.

Fig. I is a plan view of a glass plate or the like showing my new design, it being understood that the ornamentation shown in the segmental portion is continued throughout the entire circumference of the plate.

Fig. II is a plan view of the bottom central portion only of the plate.

Fig. III is a sectional view thereof taken on a diametrical plane through the plate.

The characterizing feature of my design for the glass plate shown lies in the surface ornamentation thereon.

I claim:

The ornamental design for a glass plate or the like, substantially as shown and described.

CARL T. SLOAN.
